INSULATOR AND THE LIKE

Earl H. Kendall, Jackson, Mich.

Application May 19, 1939, Serial No. 274,480

9 Claims. (Cl. 174—165)

This invention relates to insulators for use in supporting electrical conductors and particularly to an insulator arranged to have a supporting wood screw attached thereto at the time the insulator is to be mounted.

Insulators for supporting electrical wires in one manner or another are commonly provided with a lag screw or the like permanently secured thereto, and the combination is secured to a wood support by grasping the insulator with some suitable tool and rotating the same to screw into the wood. This practice is unsatisfactory not only for the reason that the strain placed on the insulator frequently results in breaking the same, but also due to the fact that as different length lag screws are required, it is necessary to maintain a stock of insulator and lag screw combinations in a great many classifications to assure that the proper type of insulator and lag screw will at all times be available. According to the present invention, these disadvantages are overcome by providing an insulator, the lag screw for which is stocked separately and is connected to the insulator at the time the insulator is mounted at a job. According to the invention, a lag screw of the desired length is screwed into the support by applying a wrench directly to its head. It is then backed off slightly and the insulator attached. To firmly connect the insulator to the support, it is then only necessary to rotate the insulator to turn the lag screw a slight amount to seat the insulator firmly against its support and have it held rigidly there by the lag screw.

Accordingly, an object of the invention is to provide an insulator arranged to have a lag screw connected thereto at the time the insulator is to be mounted on the job.

Another object of the invention is to provide a method of mounting insulators which comprises first securing a screw to the insulator support and then connecting the insulator to the screw.

A further object of the invention is to provide an insulator having a metallic insert for connection to a lag screw head.

These and other objects will be apparent from the following specification when taken with the accompanying drawing, in which

Fig. 1 is a side elevation of an insulator having a lag screw assembled thereto in accordance with one form of the invention.

Fig. 2 is a section on the line II—II of Fig. 1.

Fig. 3 is a perspective view of a removable 55

insert employed in the construction of Figs. 1 and 2.

Fig. 4 is a vertical section of another form of the invention particularly adaptable to glass insulators.

Fig. 5 is a section on the line V—V of Fig. 4, and

Fig. 6 is a perspective view of the metallic insert employed in the form of the invention disclosed in Figs. 4 and 5.

Referring particularly to the drawing, the reference character 1 indicates an insulator body in the form of a wire holder. It will be understood, of course, that the invention may be employed in association with other forms of insulators and wire holders. Accordingly, the form of insulator disclosed in the drawing is only for the purpose of disclosure. The form of the invention disclosed in Figs. 1, 2 and 3 is particularly adaptable to insulators constructed of porcelain or other ceramic material. Extending entirely through the body 1 of the insulator adjacent the base portion 2, is a transverse slot 3, similar in cross-section to the cross-section of the head 4 of the lag screw 5, adapted to be associated with the body 1, and as shown particularly in Fig. 2 wherein the head 4 of the lag screw 5 is shown as disposed within the slot 3. The head 4 is disposed in the slot 3 by passing it through a passage 6 communicating with the base of the body 1 and with the slot 3. The passage 6 is of sufficient size to permit the passage of the head 4.

In order to secure the head 4 of the lag screw 5 within the body 1, a metallic clip 7 shown particularly in Fig. 3 is provided. The clip 7 is of sheet metal and preferably is slightly resilient. It is generally tubular in form and is arranged to slidably fit into the slot 3. At the lower side 40 of the clip 7 is provided a longitudinal opening 8 for permitting the passage of the shank of the lag screw 5 as the clip 7 is moved into the slot 3. The opening 8 has a tapered portion 9 at one end thereof for guiding the shank of the lag screw 5 thereinto, and at its midportion is provided with an enlarged portion 10 for receiving the shank of the lag screw 5. The width of the opening 8, except at the tapered portion 9, is slightly less than the shank of the lag screw 5 so that in moving the clip 7 through the slot 3 the sides of the clip 7 are urged apart, when in engagement with the shank of the lag screw 5. When the enlarged portion 10 of the opening 8 reaches the shank of the lag screw 5, the sides of the clip 7 contract inwardly to resiliently lock

the clip 7 to the lag screw 5, for the purpose of preventing accidental removal thereof.

In mounting an insulator according to the present invention, the lag screw 5 is screwed into a support, usually of wood, by applying a wrench to the head 4. The distance that the lag screw 5 is screwed into the support depends on the exact type of insulator to be mounted, but in each case it will be a distance such that the head 4 projects from the support a distance slightly less than the distance which the head 4 will project when in finally assembled relation with the insulator. The lag screw 5 is then backed out, by employing a wrench on the head 4, a relatively short distance. The insulator body 1 is then placed over the head 4 in such a manner as to pass the head 4 through the passage 6 and into the slot 3. The clip 7 is moved through the slot 3 until the shank of the lag screw 5 registers with the enlargement 10 in the opening 8 of the clip 7. In this position the head 4 is maintained against withdrawal and rotation by the clip 7. The final step is to rotate the body 1 either by hand or by means of a suitable wrench to turn the lag screw 5 back into its support until the base 2 of the body 1 is firmly against the support. The insulator body 1 is then ready for use.

The form of my invention disclosed in Figs. 4, 5 and 6 is particularly adapted for association with a glass insulator or an insulator of some material wherein, for practical production reasons, it is not feasible or possible to provide a slot 3 as disclosed in Figs. 1 and 2. In this form of the invention, the body 15 is formed with a metallic insert 16 therein. The insert 16 is somewhat in the form of a box having an anchoring flange 17 and is provided at one side thereof with a keyhole slot 18. The side of the insert 16 having the keyhole slot 18 is flush with the base 19 of the body 15. The keyhole slot 18 is provided with an enlarged portion 20 of sufficient size to receive the head 21 of a lag screw 22. The restricted part 23 of the keyhole slot 18 is of such a size as to receive the shank of the lag screw 22 but to prevent downward passage of the head 21. At the juncture of the portions 20 and 23 of the keyhole slot 18, there are provided upwardly projecting flanges 24 for laterally supporting the head 21 of the lag screw 22 against movement toward the enlarged opening 20. As shown particularly in Fig. 4, the relative heights of the insert 16 and of the flanges 24 are such as to permit the head 21 to pass over the flanges 24 when the lag screw 22 is being assembled with the body 15. The size of the insert 16 and the location of the flanges 24 are such as to maintain the head 21 against rotation when within the insert 16 and in the position shown in full lines in Fig. 4.

The broad method of mounting an insulator according to the form of the invention disclosed in Figs. 4, 5 and 6 is the same as that for the form of the invention disclosed in Figs. 1, 2 and 3. The lag screw 22 is screwed into the support as of wood, or the like, by a suitable wrench applied to the head 21. In the form of the invention disclosed in Figs. 4, 5 and 6, however, it will be necessary to dispose the lag screw 22 much further into its support than in the first case for the reason that the distance from the final assembled position of the head 21 to the support is much less than it was in the first case. The lag screw 22 will have to be screwed substantially all of the way into its support. It is then backed off a sufficient distance to permit the head 21 to

clear the flanges 24 when the body 15 is disposed over the head 21 in such a manner as to pass the head 21 through the portion 20 of the keyhole slot 18. The body 15 is then moved laterally to dispose the head 21 behind the flanges 24 in the position shown in Fig. 4. Rotation of the body 15 by hand or by a suitable wrench is then all that is necessary to screw the lag screw 22 back into its support to clamp the body 15 against the support, and to make the insulator ready for use.

It will be apparent that in both forms illustrated of the invention, the strain placed upon the insulator in order to screw it tightly against the support to which it is secured is minimal due to the fact that the lag screw has already been screwed sufficiently far into the support to provide the threaded hole for the lag screw. Accordingly, when the insulator is turned the lag screw is only screwed into a threaded hole which itself has previously made. Furthermore, it will be evident that it will be possible to keep separately a stock of insulators and lag screws of the various types and sizes desired and in that manner avoid a large number of classifications of lag screw and insulator combinations. While the present invention has referred to lag screws, it will of course be understood that the equivalent of lag screws may be employed in any case where desired without departing from the scope of the claims. Accordingly, it is intended that the term lag screw in the claims be considered as sufficiently broad to include any suitable screw employable for attaching insulators to a support.

The two forms of the invention disclosed are both considered to be desirable but it will be understood that other forms within the scope of the invention may be employed. Accordingly, I do not wish to be limited except by the scope of the following claims.

I claim:

1. An insulator or the like of the character described comprising a body provided with a recess and a passage communicating with said recess, a casing in said recess for attachment to a securing element having a head, said element being adapted to be arranged in a supporting structure, said passage being for permitting the passage of said head into said recess for locking said head against rotation and against withdrawal from said recess, said casing being arranged to receive said head after said element is substantially arranged in said supporting structure.

2. In a device of the character described, a body provided with a recess and an opening communicating with said recess, for attachment to a securing element having a head, said opening being for permitting the passage of said head into said recess, and a removable resilient head embracing casing within said recess for locking said head against rotation and against withdrawal from said recess.

3. In a device of the character described, a body provided with a transverse recess and having an opening communicating with said recess, for attachment to a securing element having a head, said opening being for permitting the passage of said head into said recess, and a head embracing casing slidably in said recess arranged to receive said head when disposed through said opening into said slot, for locking the same against rotation and against withdrawal from said body.

4. The invention as defined in claim 3 wherein

the clip comprises a member tubular in form, having a longitudinal opening along one side thereof for permitting the relative passage of said element, while the head of said element moves relatively within said member.

5. An insulator or the like of the character described comprising, a body provided with a recess in one side thereof, for attachment to a securing element having a head, an insert in said recess, said insert having one side thereof adjacent the side of said body in which said recess is disposed, said last named side of said insert having a keyhole slot therein for permitting the passage of said head into said recess, and upon relative lateral movement between said head and said body for preventing removal of said head from said insert, said insert also being restricted for preventing relative rotation between said head and said body.

6. An insulator or the like of the character described comprising, an insert, said insert having on one side thereof a keyhole slot, the side of the insert having the keyhole slot being adapted to be disposed substantially flush with one face of the insulator or the like, said keyhole slot being arranged to receive the head of a securing element and having a relatively enlarged opening through which the head of the securing element is adapted to initially pass, and a restricted opening for retaining the head of the securing element against outward movement, and flange means disposed between said enlarged and restricted openings, for restricting the head of the securing element against movement from relation with said small opening toward said enlarged opening.

7. A clip of the character described comprising a member generally tubular in form, having a longitudinal opening along one side thereof, said opening being flared at one end to provide easy access, and having intermediate the ends thereof an enlarged seating portion connected to the flared portion of an opening of restricted size.

8. In combination, a portable rotatable body provided with a recess and a passage communicating with said recess, and a relatively fixed body having a screw therein, said screw having a head and being screwable with respect to said body, said passage being for permitting passage of said head into said recess, said rotatable body having a casing in said recess for locking said head against rotation and against withdrawal from said recess, whereby said screw may be threadably disposed in said relatively fixed body in a predetermined relation thereto independently of said relatively rotatable body and said relatively rotatable body detachably secured to said head and rotated to rotate said screw to draw said relatively rotatable body against said relatively fixed body.
9. In combination, a portable rotatable body provided with a recess in one side thereof, and a relatively fixed body having a screw therein, said screw having a head and being screwable with respect to said body, said recess having an insert therein, said insert having one side thereof adjacent the side of said relatively rotatable body in which said recess is disposed, said last named side of said insert having a keyhole slot therein for permitting the passage of said head into said recess, and upon relative lateral movement between said head and said body for preventing removal of said head from said recess, said insert also being restricted for preventing relative rotation between said head and said body, whereby said screw may be threadably disposed in said relatively fixed body in a predetermined relation thereto independently of said relatively rotatable body and said relatively rotatable body detachably secured to said head and rotated to rotate said screw to draw said relatively rotatable body against said relatively fixed body.

EARL H. KENDALL.
